HER ATTORNEY.

UNITED STATES PATENT OFFICE.

SUSANNE G. BRENNAN, OF HIGHLAND PARK, MICHIGAN.

ABDOMINAL SUPPORTER.

1,359,573.

Specification of Letters Patent. Patented Nov. 23, 1920.

Application filed February 3, 1919. Serial No. 274,720.

To all whom it may concern:

Be it known that I, SUSANNE G. BRENNAN, a citizen of the United States, residing at Highland Park, county of Wayne, State of Michigan, have invented a certain new and useful Improvement in Abdominal Supporters, and declare the following to be a full, clear, and exact description of the same, such as will enable others skilled in the art to which it pertains to make and use the same, reference being had to the accompanying drawings, which form a part of this specification.

My invention relates to a class of surgical appliances which are termed abdominal supporters and it consists in a peculiar construction and arrangement of its parts which is hereinafter described and claimed.

In the drawings:

20 Figure 1 is a perspective view of the supporter opened out.

Fig. 2 is a perspective front view of the supporter in position.

Fig. 3 is a left hand side view of the supporter in position.

Similar letters refer to similar parts.

In the drawings A represents the right hand edge of the device and B the left hand edge. In use these two surfaces are brought together with the edge of B overlapping. An edge C is carried beyond the lacing strip. D D are, preferably, holes although they might be hooks in order to afford a means for lacing the article by means of lacing strip E. In connection with the lacing strip is an elastic inclosed within the body of the supporter. Elastic strips are also placed diagonally at G G at the back; there are also elastic strips H embodied in the fabric but also attached thereto are two elastic bands J and K which are flexible and firmly attached to the two parts of the article. It will be noted that the strips H H are not parallel but are at an angle so that one of the bands K is longer than the band J. At L the upper band J overlaps the band K.

The object of this construction is that the same character of elastic bands J and K may be used but J being shorter than K on adjust-

ing the band it creates a greater pull than K and without the danger of wrinkling. If the bands J and K are all in one piece and one part narrower than the other the pull upon the band would be liable to wrinkle. It will be noted that the supporter in its 55 form is such that the bands pass around the small of the back, as shown in the figures, the longer band K being lower than the band J and that when laced the elasticity of the bands tends to draw upwardly upon the 60 front portion, especially its lower part at E'. This may be to a certain extent modified by the lacing. It will be noted that the stays G G are not parallel but are wider apart at the lower part of the supporter 65 than they are at the top. This will enable the supporter to fit over the hip, the stays generally prevent its wrinkling up the upper and lower edge approaching each other thereby. Hose supporters M M are attached 70 to the front in proper position if desired.

What I desire to claim is:

1. In an abdominal supporter, a combination of two inelastic fabric side portions so cut in the rear that the intervening space 75 therebetween diverges from top to bottom, means for uniting said side portions in front, an elastic back portion uniting said side portions in the rear composed of two independent elastic sections, one of said sections overlapping the other, and the upper 80 of said sections being shorter than the lower.

2. In an abdominal supporter, the combination of two inelastic fabric side portions constantly widening as they approach the 85 front and provided with means for being united in front, the rearward edges of said side portions cut on a bias diverging from each other from top to bottom, an elastic web back portion composed of two independent sections joining such side portions cut in a like bias, one of said portions overlapping the other, the upper of said sections being shorter than the lower.

In testimony whereof I sign this specification.

SUSANNE G. BRENNAN.
